UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

OPERATING VAPOR ELECTRIC APPARATUS FROM AN ALTERNATING-CURRENT SOURCE.

1,110,847. Specification of Letters Patent. Patented Sept. 15, 1914.

Application filed October 18, 1902. Serial No. 127,834.

To all whom it may concern:—Be it known that I,

EZECHIEL WEINTRAUB, a subject of the Czar of Russia, residing at Schenectady, County of Schenectady, State of New York, have invented certain new and useful Improvements in Operating Vapor Electric Apparatus from an Alternating-Current Source, of which the following is a specification.

It has been heretofore found impossible to operate electric vapor lamps from sources of alternating electro-motive force of moderate value, owing probably to the fact that the lamp must be started each time the voltage passes through zero and commences to rise in the opposite direction. The alternating electromotive force, unless of relatively excessive value, such for example as one to two thousand volts, is incapable of initiating and maintaining an electric discharge in the lamp. I have found, however, that if by supplemental means ionized vapor be produced in the lamp, this vapor serves to initiate an electric discharge between the terminals of the lamp to which a moderate alternating electro-motive force may be applied. This ionized vapor being produced through the agency of a direct current, apparently serves to render the lamp conducting for alternating waves of one polarity but not of the opposite polarity, since I find in practice that the current flowing under such conditions consists of a series of intermittent waves of one direction corresponding to the waves of one direction of the alternating electro-motive force, the waves of opposite direction being suppressed.

My invention therefore renders it possible to operate a mercury or other vapor electric lamp with alternating electro-motive forces either for the purpose of producing light or for utilizing the uni-directional currents set up by the alternating electro-motive forces through the lamp, in which case my invention operates as a rectifier, or for both purposes simultaneously.

The scope of my invention both as to its broader features of novelty and the more limited details thereof, will be made clearer by reference to the claims appended hereto, while the invention itself, as to its construction and mode of operation, will be set forth in detail in the following description which

is to be taken in connection with the accompanying drawings in which—

Figure 1 represents one embodiment of my invention; Fig. 2 another form of my invention; and Fig. 3 a third embodiment of my invention.

In Fig. 1 a mercury electric lamp is indicated at 1 and illustrates one of the various forms of vapor lamps in connection with which my invention may be practised. This particular lamp is so constructed as to operate in a horizontal or slightly inclined position as indicated. The lamp consists of an exhausted envelope or receptacle 1 having a depending portion 2 at one end filled with mercury and forming a terminal or electrode, and a pair of depending portions 3-4 at the other end containing bodies of mercury or other suitable material for forming two other terminals or electrodes. The depending portions 3 and 4 are substantially filled with bodies of mercury 5 and 6 having top surfaces adjacent to each other. A source of direct current, such for example as a storage battery 7, is connected to leading-in wires 8-9 making contact respectively with the two bodies of mercury mentioned. By a slight agitation of the tube or by other means, the two bodies of mercury may be made to flow momentarily into contact with each other so that upon the breaking of the contact as the mercury flows back, an arc or discharge is produced within the tube which arc may be maintained indefinitely. A source of alternating electro-motive force, such for example as single phase alternating current generator 10, is connected in a circuit, one terminal of which leads to the outer or positive electrode 2 of the lamp and the other terminal of the circuit to one of the two remaining terminals of the lamp such for example as the leading-in wire 9 connected to the negative electrode 6. When the electric discharge or supplemental arc is being maintained in the tube by the storage battery 7 or other source of direct current, I find

that the alternating current generator 10 is enabled to initiate and maintain a discharge through the main body of the tube 1. The current flowing in the circuit of the alternating current generator I find, as before mentioned, to be unidirectional in character.

and to consist of a series of disjointed waves of one direction. The waves of electro-motive force of opposite direction are not permitted to set up corresponding waves of current. To utilize the uni-directional current from the generator 10 I may employ any suitable current consuming or translating devices such for example as a storage battery 11 in the work circuit in series with

the generator.

Instead of employing the particular form of lamp shown in Fig. 1, I may if desired use that shown in Fig. 2 in which the main tube 12 of the lamp is upright in position, the two cooperating terminals for producing the auxiliary or supplemental arc or discharge being located at the bottom of the tube and the remaining terminal at the top. The two electrodes 12' and 13 at the bottom 20 of the tube are formed by adjacent bodies of vaporizable material as mercury separated by a slight ridge 14 over which the mercury may be momentarily caused to pass in order to connect the terminals together and 25 establish the arc. Current is supplied to these two mercury terminals through corresponding leading-in wires 15, 16 between which the source of direct current such as the storage battery 17 may be connected. 30 The upper or positive terminal or electrode of the lamp, instead of being of mercury, corresponding to the terminal 2 in Fig. 1, may be of some solid conducting material such for example as iron or steel and formed 35 into a bell-shaped body 18 to which current may be supplied through the leading-in wire 19. The leading-in wire 19, which constitutes the upper external terminal of the lamp, may operate in conjunction with one 40 of the lower terminals of the lamp such as 15 to receive current from an alternating current source such for example as the generator 20, the operation being substantially the same as that described in connection 45 with Fig. 1. As before, a storage battery or other translating device 21, may be utilized to receive the rectified or uni-directional current derived from the alternating current generator 20.

In case it be not desired to obtain a rectified or unidirectional current for purposes other than producing light in the lamp, I may omit the storage battery or energy-absorbing or consuming device 21 as indicated in Fig. 3. In this case the lamp proper indicated at 22 may be made of any desired length as indicated conventionally by the broken away portion 23. When of a considerable length, I find that the use of 50 a long carbon filament 24 extending from the upper electrode 25 into proximity to the lower electrode 26 assists in starting and in maintaining the arc, as set forth in applications heretofore filed by me. The filament 55 may however be omitted if desired.

If the apparatus which I have above described is to be used chiefly or solely as a rectifier, I find that the lamp may be made shorter without impairing its value as a rectifier than when it is intended also or 70 principally to give light, in which latter case it may be made of relatively large dimensions to correspond to the amount of light desired.

What I claim as new and desire to secure 75 by Letters Patent of the United States, is,

1. The combination with a vapor electric lamp, of an alternating current circuit connected to terminals thereof, and a source of direct current also connected to terminals of the lamp so as to set up ionized vapor in the lamp whereby a conducting path is furnished for waves of the said alternating current of one polarity only.

2. The combination of a vapor electric lamp, a source of alternating electro-motive force connected to terminals of said lamp and insufficient of itself to set up a discharge in the lamp between said terminals, and means for permitting waves of current of one polarity only from said source to flow in said lamp.

3. The combination of a vapor electric lamp, a source of alternating electro-motive force connected to terminals of the lamp and incapable of itself either of initiating or of maintaining a flow of energy in said lamp between said terminals, and separate means for rendering the lamp a conductor for current from said source.

4. The combination of a vapor electric lamp, a source of alternating electro-motive force connected to terminals of said lamp, and means for projecting ionized vapor into the vicinity of said terminals, which vapor serves as a carrier to initiate and to maintain an electric discharge at the expense of energy derived from said source.

5. An alternating current rectifier comprising an exhausted envelop through which the alternating electro-motive force is, insufficient of itself to initiate a flow of current, and electrical means for rendering said envelop conductive for currents of one direction only.

6. The combination of a vapor electric lamp provided with three terminals, a source of direct current connected to two of the terminals and adapted to maintain an electric discharge in the lamp between said two terminals, a source of alternating electro-motive force connected in a circuit between the remaining terminal and one of the other terminals, and a device for utilizing uni-directional current in said circuit.

7. The combination of a vapor electric apparatus, source of alternating electro-motive force of a value insufficient when operatively related to terminals of the apparatus to start or maintain a discharge therein, and supple-

mental means for generating ionized vapor in the lamp, the presence of which operates to permit a uni-directional flow of current between said terminals under the influence 5 of said alternating electro-motive force.

8. The method of causing a unidirectional flow of current from an alternating current source between electrodes, one at least of which is of vaporizable material, which consists in continuously maintaining an arc springing from the vaporizable electrode independently of said flow of current from 10 said alternating current source.

9. The method of causing a unidirectional flow of current from an alternating current source between electrodes associated with 15 said source, one at least of which electrodes is of vaporizable material, which consists in producing and continuously maintaining an 20 arc from the vaporizable electrode through the agency of direct current.

10. The method of causing a unidirectional flow of current from an alternating current source between electrodes associated 25 with said source, one at least of which electrodes is of vaporizable material, consisting in continuously generating ionized vapor from said vaporizable electrode through the agency of direct current.

11. The method of causing an arc or current flow between electrodes connected to a source of alternating current, one of which electrodes is of vaporizable material, which consists in continuously maintaining an arc 35 springing from the vaporizable electrode thereby enabling the alternating current source to set up a flow of current between said electrodes.

12. The combination of electrodes, one at 40 least of which is of vaporizable material, a source of alternating electro-motive force connected to said electrodes, and means independent of said source for causing current therefrom to flow between said electrodes.

13. The combination of an exhausted envelop, alternating current electrodes for said envelop, and means independent of the source of alternating current connected to 50 said electrodes for causing current from the alternating current source to flow through the envelop.

14. The combination of electrodes, a source of alternating current connected to said electrodes, a supplemental electrode coöoperating 55 with one of the first mentioned electrodes, and a source of direct current connected to the supplemental electrode and its coöperating electrode.

15. The combination of an exhausted envelop or receptacle, electrodes therefor, one at least of which is of vaporizable material, a source of alternating current connected to 60 said electrodes, and means for continuously maintaining an arc at the vaporizable electrode for causing current from said alter-

nating current source to flow through said envelop.

16. The combination of a source of alternating electro-motive force, an exhausted receptacle, electrodes therefor, one of said electrodes being of vaporizable material, connections between said source and said electrodes, and means independent of current flow from said source between said electrodes for continuously maintaining an arc 70 at said vaporizable electrode.

17. The combination with a source of alternating electro-motive force, electrodes in fixed relation to and separated from each other, and a source of direct current for producing an electric discharge or current flow along a path including one of said electrodes.

18. The combination of a source of alternating electro-motive force, a plurality of electrodes, one at least of which is of vaporizable material arranged in fixed relation to and separate from each other, connections between said electrodes and said source of alternating electro-motive force, and means independent of said source for generating 90 ionized vapor from said vaporizable electrode.

19. The combination of a source of alternating electro-motive force, a plurality of electrodes, one at least of which is of vaporizable material, arranged in fixed relation to and separate from each other, connections between said electrodes and said source of alternating electro-motive force, and a source of direct current for producing current flow 100 in a circuit including said vaporizable electrode.

20. The combination of an exhausted envelop, single phase electrodes for said envelop, and supplemental means for continuously generating ionized vapor in said envelop.

21. The combination of an exhausted envelop or receptacle, single phase electrodes therefor, at least one of which is of vaporizable material, and a source of direct current coöperating with a vaporizable electrode for producing ionized vapor in said envelop.

22. The combination of an inclosing chamber, a plurality of positive electrodes, a negative electrode, and an intervening gas or vapor, a source of alternating electric currents connected with one or more of the positive electrodes and with the negative electrode, and a source of continuous currents having its respective poles connected with a positive electrode and the negative electrode.

23. The combination of an inclosing chamber, a plurality of positive electrodes, a negative electrode, and an intervening gas or vapor, a source of alternating electric currents connected with one of the positive electrodes and with the negative electrode, a source of continuous currents having its re- 125
